ATTACHMENT FOR LOCKS

Virgil Sidney Downing, Jackson, Miss., assignor
of one-third to Joseph W. Roell and one-third
to Stewart Gammill, both of Jackson, Miss.

Application June 26, 1935, Serial No. 28,512

15 Claims.

(Cl. 116—8)

This invention relates to attachments for locks.

An object of the invention is the provision of a device adapted to be attached to a lock for causing an alarm to be set in action when an unauthorized person attempts to enter a room by a master or skeleton key.

Another object of the invention is the provision of a device adapted to be attached to the inner face of a door of a room either in a private or public building for causing an alarm to be set in action when some unauthorized person attempts to enter the room by a master key after a night latch has been placed in operative position by the occupant of the room, no modification of the lock being required for the application of the device since the attachment has elements so constructed that they may be placed in operative relation with the operating cam of the lock.

A further object of the invention is the provision of a device which may be readily placed in operative relation with the operating cams of a lock whereby an alarm will be set in operation when a master key has been employed for causing the reciprocation of a pair of lock bolts from operative relation with the keeper on the door frame, means being employed which is not readily detectable from the exterior for resetting the alarm or for cutting off the alarm when necessary.

A still further object of the invention is the provision of a device which is formed as a unit and which may be readily placed in operative relation with an operating cam of a lock whereby an arm may be set in operation when a master key is used for causing reciprocation of the locks from the exterior of a room, said device including a spring-pressed plunger adapted to be adjustably positioned into the path of the cam for releasing the operating mechanism for the alarm when said plunger is rocked by the cam, the plunger being so constructed that the master key may operate the cam in an opposite direction for throwing the locking bolt into an operative position without setting the alarm in action.

Another object of the invention is the provision of a device for creating an alarm to frighten unauthorized persons who are attempting to enter a room by means of a master key which is capable of not only releasing the bolt normally operated from the inside by a knob, but which is capable of throwing a locking bolt connected with a night latch which is normally moved to

an operative position by the occupant of a room before retiring.

This invention will be best understood from a consideration of the following detailed description, in view of the accompanying drawings forming a part of the specification; nevertheless, it is to be understood that the invention is not confined to the disclosure, being susceptible of such changes and modifications as define no material departure from the salient features of the invention as expressed in the appended claims.

In the drawings:

Figure 1 is a view in perspective of a door lock attachment constructed in accordance with the principles of my invention.

Figure 2 is a longitudinal vertical section of a lock and the attachment,

Figure 3 is a vertical section taken along the line 3—3 of Figure 4,

Figure 4 is a vertical section taken along the line 4—4 of Figure 3,

Figure 5 is a fragmentary vertical section taken along the line 5—5 of Figure 3,

Figure 6 is a view in perspective of the spring motor,

Figure 7 is a vertical section taken along the line 7—7 of Figure 2,

Figure 8 is a vertical section taken along the line 8—8 of Figure 2,

Figure 9 is a vertical section taken along the line 9—9 of Figure 2,

Figure 10 is a horizontal section taken along the line 10—10 of Figure 2,

Figure 11 is a fragmentary enlarged view in elevation of the tripping means for the alarm, and

Figure 12 is an enlarged view in perspective of the tripping mechanism.

Referring more particularly to the drawings, 20 designates a door which may be used in connection with dwellings, hotels, or apartments and is provided with a lock casing 21 mounted within a pocket 22 formed in the door. This lock is provided with an outer knob 23 which is in the form of a dummy and has no effect whatever on the lock mechanism for shifting the usual lock bolts.

A knob 24 is located within the room and is adapted to shift a lock bolt 25 inwardly of the metal facing plate 26 on the vertical edge of the door 20 when said knob is revolved whereby the door may be opened from the interior.

A night latch lock is included within a barrel

27 which is threaded at 28 in an opening in the casing 21. A face plate 29 is secured to the outer face of the door 20.

The lock barrel 27 is usually of the permutation type so that only a certain kind of key may be inserted in the usual slot in the barrel for operating cylinders which are connected to cam 30 for causing shifting of the lock bolt 25 by a mechanism (not disclosed) and which forms no part of the present invention. A cam 31 is so associated with the cam 30 that it may be operated by the master key for reciprocating a bolt 32 which had been moved to an operative position with the keeper on the door jamb by means 10 of a handle 33 by the occupant of the room. The lock bolt 32, however, is never on when the door 21 has been closed and no one is in the room since it is of the type which can only be shifted to an operative position, on the one hand, by a partial rotation of the member 33 or on the other hand by the master key.

It should be borne in mind that when a guest of a hotel has engaged a room he is given a key which may be inserted in the slot in the barrel 27 for operating the cam 30 which will reciprocate the bolt 25 from the exterior of the room. On the other hand, if the hotel manager desires to enter the room for some reason after the lock bolt 32 has been moved to an operative position 30 by the handle 33 it will be necessary for such person to use a master key which will not only rock the cam 30 but will rock the cam 31 in advance of the rocking of the cam 30 so that both lock bolts 25 and 32 will be shifted to an inoperative position.

All the parts just described relate to standard lock constructions and therefore form no part of the present invention. My invention, however, is enclosed within a housing generally designated 40 by the numeral 35 and is attached to the inner face of the door and normally sealed against unauthorized removal although an element projects from the casing into a spirally constructed pocket 36 of the door 20 and is adapted to be operated 45 by the cam 31 to set an alarm in operation.

The housing 35 consists of a shallow portion 37 and a portion 38 of greater depth. This housing is provided with a base plate, generally designated by the numeral 39.

50 The base plate is secured to the inner face of the door 20 by means of screws 40 and this base plate is provided with an outwardly projecting bracket 41 to which is bolted, as shown at 42, a bar 43 which is secured in any approved manner to the side walls of the portion 38 of the housing 35. It will be noted that the bolts 42 are located directly opposite a door 44 which closes an opening that provides an entrance to the housing at this point, so that when the door 60 44 is unlocked and not until then the bolts 42 may be removed by a suitable tool.

The door 44 is provided with a lock 45 which has a lock bolt 46 adapted to engage the inner face of the auxiliary portion 38 of the housing and prevents the door from being opened until a suitable key has been inserted in the slot 47 of the door 44.

70 The auxiliary housing, as shown in Fig. 1, is provided with guides 48 which are adapted to receive a metal plate 49 having advertising matter on its surface so that the door 44, together with its key slot, is normally hidden from view. When the plate 49 has been raised or withdrawn the door 44 will be exposed to view.

The base plate 39, as shown in Fig. 2, is provided with a passage 50 to receive a shaft 51 connected with the handle 33. This base member is also provided with a passage 52 adapted to receive a shaft 53 which is connected to the 5 knob or handle 24. The opening 50 when aligned with the opening at the inner end of the barrel 27 and the opening 52 has been aligned with an opening 54 in the door 20 will indicate to the workman that the plate 39 has been properly 10 positioned on the inner face of the door since the shafts 51 and 53 must pass through these openings and the positions of these shafts have been 15 previously determined by the position of the lock when originally placed in the door.

An alarm is located within the portion 38 of the housing 35 and includes a motor, generally indicated by the numeral 55, and a bell which as shown in Fig. 2 is secured to a lug 57 carried by the inner face of the member 38 and held to 20 said lug by means of a screw 58.

The motor 55 includes a casing 60 which has lugs 61 at its inner periphery cooperating with lugs 62 on a cover plate 63 for securing the cover plate to the open end of the casing.

A sleeve 64 is threaded with left hand threads, as shown at 65, into the outer face 66 of the casing 60 and is provided with a shoulder 67 adapted to engage the outer face 66.

A hollow axle 70 passes through openings in 30 the cover plate 63 and the outer face plate 66 and is received by the sleeve 64 which acts as a bearing for the outer end of the axle. This axle is formed integrally with a base plate 71 which is shown at 72 as secured to the base plate 39 of 35 the housing 35.

As shown more particularly in Figs. 3 and 4, a spring 73 is coiled within the casing 60 and has one end secured to a lug 74 projecting from the axle 70. The other end of the spring, as shown 40 at 75, projects through an opening 76 in the casing 60 and is turned for securing the outer end of the spring to the casing.

A winding key 77 is provided with an operating handle 78 and is adapted to be inserted within the sleeve 64 so that a diametrically disposed pin 79 will be received within slots 80 in the outer end of the sleeve 64. Thus when the handle 78 is revolved the sleeve will be revolved and likewise the casing 60 for winding up the spring 73.

55 A pawl 81 is pivotally mounted at 82 on the cover plate 63 of the casing 60 and has its free end moved inwardly into the teeth of a ratchet wheel 83 which is loosely mounted on the axle 70. Thus it will be seen that when the motor 55 is 55 revolved in the direction indicated by the arrow in Fig. 4, the spring will be wound upon the axle 70 while the pawl 81 rides over the teeth of the ratchet wheel 83. A spring 84 is adapted to maintain the pawl 81 in engagement with the teeth of 60 the ratchet wheel.

A gear 85 is secured to the ratchet wheel 83 and is maintained in spaced relation with the base plate 71 which is connected to the barrel 70 by means of a washer 86 provided with a flange 87 65 which is in contact with the gear 85 and the flange is of sufficient diameter to maintain the gear 85 in a predetermined position.

70 It will be noted that the washer 86, the gear 85, the ratchet wheel 83 and the cover plate 63 70 of the casing 60 are provided with slots, generally indicated by the numeral 88, to permit the insertion of the lug 74 into proper position when these elements are placed on the axle 70.

75 It will be noted that the outer end of the sleeve 75

64 is located in alignment with the door 44 in the portion 38 of the housing 35 so that when the door is unlocked the key 77 may be inserted for rewinding the motor.

5 A series of gears cooperatively mesh for revolving the shaft 90 as shown in Figs. 7 and 8. The gear 85 meshes with a pinion gear 91 secured to a gear 92 meshing with a pinion gear 93 secured to a gear 94. The last-mentioned 10 gear meshes with a pinion 95 secured to the shaft 90. A gear 96 secured to the shaft 90 meshes with the locking gear 97 carried by the base plate 39.

15 A bracket 98 which is secured to the base plate 39 is adapted to support the upper ends of the shafts of the pinion gears 91 and 93. This bracket also supports the upper end of the shaft 90 and this shaft projects outwardly of the bracket plate for receiving a clapper 99 which is in 20 the form of a governor and this governor is housed within the bell 56.

25 The governor consists of diametrically disposed arms 100 which are connected to the shaft 90 by means of a nut 101, the governor resting upon a shoulder 102 connected to the shaft 90. As shown more particularly in Fig. 2, these arms 100 are spaced apart to receive weighted discs 103 which have central openings of greater diameter than lugs 104 so that these discs will be thrown outwardly by centrifugal force when the arms are being revolved at a predetermined speed. As 30 these discs are thrown outwardly they alternately strike a lug 105 which is punched from the metal of the bell and which projects into the path of the moving discs. Each of the lugs 104 is struck up from the inner arm 100 and projects through an opening 106 at each end of the outer arm 100.

35 A tripping mechanism, shown more particularly in Figs. 11 and 12, consists of a lever 110 which is pivoted intermediate its ends, as shown at 111, to the base plate 39. The upper end of the lever is provided with a notch 112 which is adapted to engage with the teeth of the pinion 97. When the notch is so engaged all of the gears 91 to 97, inclusive, are held against rotation as is the gear 85 and the motor 55.

40 An arm 113 projects from one edge of the lever 110 below its pivot 111 and is provided with a guide 114 which receives a rod 115. A set screw 116 secures the rod 115 within the guide and in 45 an adjusted position for a purpose which will be presently explained. A stop 117, secured at 118 to the base plate 39, is adapted to engage the arm 113 for limiting the movement of the arm and likewise the lever 110. The screw and guide are located outwardly of the base plate 39 so that the rod may be adjusted and the screw set conveniently from the exterior.

45 A barrel 120 projects from the inner end of the rod 115 and carries a slidably mounted plunger 121 and a spring 122 located within the barrel tends to force the plunger outwardly. A head 123 is carried by the lower end of the plunger and is provided with a cam face 124 for a purpose which will be presently explained.

50 A rod 125 is pivotally connected to the lever 110 by a pin 126 to which one end of a spring 127 is attached. The other end of the spring is attached to a pin 128 secured to the base plate 39. The rod 125 extends across the base plate and projects through an opening 129 at one side wall 130 of the housing 35 and also through an opening 129a in a flange 130a on the plate 39. This rod is provided with a shoulder 131 which is adapted to engage one edge 132 of a keeper 133

5 formed on the inner face of the flange 130a as shown in Fig. 11 for maintaining the rod in its shifted position. A spring 135 pulls downwardly on the rod 125 and has one end connected at 136 to the base plate 39 so that the shoulder will be 5 in a position to engage the keeper 133.

10 The operation of my device is as follows: As has been previously explained the door may be opened from the exterior by means of the regular key given to the guest of a hotel or by a master key. The key carried by the guest, however, will not release both lock bolts 32 and 25 but these lock bolts can only be reciprocated by the master key. However, the key held by the guest is sufficient for his purpose since it will release the bolt 25. The night latch by means of 15 the handle 33 can only be operated from the interior of the room for moving the bolt 32 into operative relation with its keeper in the door frame so that the bolt is never in locking position when the guest is out of the room.

20 After the guest has entered the room and before he retires for the night he will usually revolve the handle 33 and this will cause the bolt 32 to be moved into operative relation with its keeper. The alarm mechanism, however, is in the position shown in Fig. 7 with the rod 125 moved inwardly of the housing 35 so that the notch 112 at the upper end of the lever 110 is in engagement with the teeth of the wheel 97. 30 In this position, and with the motor spring wound, the motor will be held against rotation. It is taken for granted, however, that the motor has been wound. This is accomplished by raising the slide plate 49 so that the door may be opened 35 with the proper key and the key 77 inserted with in the sleeve 64 whereby the spring is wound.

35 If some unauthorized person should attempt to enter the room while the guest is in the room by means of a master key the cam 31 will be first 40 rotated. When the unauthorized person attempts to operate the lock by a master key the cam 31 will immediately engage the head 123, as shown in Figs. 11 and 12 and rock the barrel 120, thereby rocking the lever 110 so that the rod 45 125 will be shifted outwardly and cause the shoulder 131 to engage the edge 132 of the keeper 133.

40 As soon as the lever 110 is rocked the notch 112 at the upper end of the lever will be moved out of engagement with the teeth of the wheel 97 so 50 that the gearing will be free to revolve whence the motor 55 will revolve the ratchet wheel 83, the gear 85 and the train of gears connected with the shaft 90. Since the governor 99 is connected to the shaft 90 the arms 100 will be revolved, 55 causing the discs 103 to be thrown outwardly and alternately strike the lug 105 on the bell 56. The ringing of the bell will warn the guest that somebody is attempting to enter his room. The bell will continue ringing until the spring 73 is un- 60 wound since the rod 125 will hold the lever 110 in released position.

55 If for some reason the unauthorized person should attempt to turn the key in a reverse direction, thinking that it may be possible to turn off 65 the alarm, the cam 31 will be rocked likewise in the opposite direction and will engage the inclined face 124 of the head 123 and thus merely move the head upwardly towards the barrel 120 without causing rocking of the barrel or the 70 lever 110.

60 The alarm is of sufficient intensity to frighten the intruder away from the door and a series of perforations 150 are formed in the side wall 130 of the housing 35 to permit the sound to readily 75

escape from said housing. In order to reset the alarm it is only necessary for the operator to raise the projecting end of the rod 125 to release it from the catch 133 whereby the spring 127 will return the lever 110 to its operative position and cause the notch 112 to engage the teeth of the wheel 97.

The plate 49 is raised and when the door 44 has been unlocked the key 71 may be inserted and the spring wound to an operative position.

The cams 30 and 31 are of the usual construction in this form of lock mechanism and both of these cams must be revolved for releasing first the lock bolt 32 and then the lock bolt 25. An authorized person who is familiar with the alarm may readily release the alarm by raising the outer end of the rod 125 to cut off the motor. The lock bolts 32 and 25, however, can only be operated from the outside by the usual master key for the purpose.

The base plate 39 is secured to the inner face of the door by a plurality of screws 40. Since the cover plate or housing 35 is secured to the base plate by means of the screws or bolts 42 it is not possible for someone to remove the cover plate or housing without unlocking the door 44. It will be noted that every precaution has been taken for preventing unauthorized persons from inspecting the interior of the mechanism without destroying certain parts.

The shaft 51 is flat and is adapted to be received within passages in the cams 30 and 31. The pin 33^a is diametrically disposed in the shaft 51 and extends upon opposite sides of the same and is adapted to engage the inner face of the cover plate 35 so that the shaft and handle 33 form a unit with the cover plate and may be removed with said cover plate. The openings 50 and 52 in the base plate 39 determine the proper positioning of the base plate on the inner face of the door so that when the opening 50 is aligned with the openings in the cams 30 and 31 and the opening 52 is in line with the opening 54 in the door 20, the base plate has been properly positioned.

Instead of the spring-wound motor 55, an electrically operated motor may be substituted and the lever 110 when rocked by the plunger 121 will close a circuit to the motor. The closing of the circuit may also warn the clerk at the desk that some unauthorized person is attempting to enter the room.

When the master key is revolved in one direction it will rock the cam 31 in the same direction and thereby release the bolt 32. When the alarm has been set, however, the lever 110 will be released through the rocking of the plunger 121 and cause the alarm to be operated. If, however, the operator turns the master key in the opposite direction the cam 31 will ride beneath the inclined face of the plunger 121 and force the same into the barrel against the tension of the spring without rocking the lever. This reverse movement of the master key, however, will throw the locking bolt 32 into an operative position with the keeper on the door jamb so that it is possible for a hotel detective or watchman to throw this bolt to an operative position without disturbing the alarm. While the key has been defined as a master key it can be more properly described as an emergency key which is owned by the hotel or other tenanted building and is adapted to be used by some authorized person in the building to unlock the door when the tenant or guest is in a room and fails to respond to calls in the usual manner.

It is understood, however, that the guest has turned the knob 33 and has thrown the auxiliary keeper in place whereby the alarm mechanism will be set for operation when the emergency key is employed from the exterior of the room.

I claim:

1. In a lock having a cam adapted to be rocked by a master key only for releasing a locking bolt, the combination of a motor, an alarm actuated by the motor, means for retaining the motor against operation, and means in the path of the moving cam adapted to be rocked by said cam and operatively connected with the last-mentioned means for releasing the retaining means.

2. In a lock having a cam adapted to be rocked by a master key only for releasing a locking bolt, the combination of a motor, an alarm actuated by the motor, a lever having means for retaining the motor against operation, and means connected with the lever and rocked by the cam for releasing the retaining means.

3. In a lock having a cam adapted to be rocked by a master key only for releasing a locking bolt, the combination of an alarm, means for operating the alarm, means for restraining the operating means, and a trip means actuated by the rockable cam for causing release of the restraining means, and means at the room side of the lock for causing shifting of the bolt to locking position.

4. In a lock having a cam adapted to be rocked by a master key only for releasing a locking bolt, the combination of an alarm, means for operating the alarm, means for restraining the operating means, a trip means actuated by the rockable cam for causing release of the restraining means, and means for retaining the restraining means in an inoperative position.

5. In a lock having a cam adapted to be rocked only by a master key for releasing a locking bolt, the combination of an alarm, an operating means for the alarm, a pivotally mounted lever, means on the lever engageable with an element of the operating means for retaining the operating means inactive, means located in the path of the rockable cam connected with the lever and adapted to be rocked by the cam for moving the lever to an inoperative position, and means for retaining said lever in the inoperative position.

6. In a lock having a cam adapted to be rocked only by a master key for releasing a locking bolt, the combination of an alarm, an operating means for the alarm, a pivotally mounted lever, means on the lever engageable with an element of the operating means for retaining the operating means inactive, means located in the path of the rockable cam, connected with the lever and adapted to be rocked by the cam for moving the lever to an inoperative position, a rod having one end pivotally connected to the lever, and a latch means for retaining the rod against movement when the lever has been rocked.

7. In a lock having a cam adapted to be rocked only by a master key for releasing a locking bolt, the combination of an alarm, a motor, an actuating means for the alarm, a gear train operatively connected between the actuating means and the motor, a pivotally mounted lever having means engageable with one of the gears of the train for retaining the motor against operation, and means actuated by the cam for causing release of the lever when the cam is rocked.

8. In a lock having a cam adapted to be rocked only by a master key for releasing a locking bolt, the combination of an alarm, a motor, an actuating means for the alarm, a gear train operatively

connected between the actuating means and the motor, a pivotally mounted lever having means engageable with one of the gears of the train for retaining the motor against operation, means actuated by the cam for causing release of the lever when the cam is rocked, and means actuated by the lever for retaining the lever in an inoperative position.

9. In a lock having a cam adapted to be rocked only by a master key for releasing a locking bolt, the combination of an alarm, a motor, an actuating means for the alarm, a gear train operatively connected between the actuating means and the motor, a pivotally mounted lever having means engageable with one of the gears of the train for retaining the motor against operation, means actuated by the cam for causing release of the lever when the cam is rocked, a rod connected to the lever and moved by the lever when rocked, and means for releasably retaining the rod and likewise the lever in position when said lever has been moved to an inoperative position.

10. In a lock having a cam adapted to be rocked only by a master key for releasing a locking bolt, the combination of an alarm, a base plate for supporting the alarm, a motor for operating the alarm, a lever pivoted on the plate and adapted to retain the motor against operation, an arm projecting from said lever and provided with a barrel, a spring-pressed plunger projecting from the barrel and into the path of the cam, said cam engaging the plunger when rocked in one direction for oscillating the lever to release the motor, and means for releasably retaining the lever in an inoperative position.

11. In a lock having a cam adapted to be rocked only by a master key for releasing a locking bolt, the combination of an alarm, a base plate for supporting the alarm, a motor for operating the alarm, a lever pivoted on the plate and adapted to retain the motor against operation, an arm projecting from said lever and provided with a barrel, a spring-pressed plunger projecting from the barrel and into the path of the cam, said cam engaging the plunger when rocked in one direction for oscillating the lever to release the motor, the projecting end of the plunger having a cam face adapted to be engaged by the cam when rocked in the opposite direction so that the plunger will be forced into the barrel without moving the lever.

12. In a lock having a cam adapted to be rocked only by a master key for releasing a locking bolt, the combination of an alarm, a motor for operating the alarm, means for retaining the motor against operation including a rockable lever, a barrel carried by the lever, a spring-pressed plunger in the barrel and having an end projecting across the path of the rockable cam, said plunger and likewise the lever adapted to be rocked by the cam for releasing the retaining means, said plunger having an inclined face over which the cam will ride in one direction of rotation and force the plunger into the barrel so that the bolt may be shifted into locking position without rocking the lever. 15

13. In a lock having a cam adapted to be rocked only by a master key for releasing a locking bolt, a base plate, an alarm, means for operating the alarm, means for retaining the operating means against motion including a pivoted lever, a rod pivoted to the lever, said rod having a shoulder, a catch on the base plate adapted to engage the shoulder and retain said rod in an operative position, resilient means tending to move the rod to an inoperative position and the lever to an operative retaining position for the lever, and means connected with the lever and rocked by the cam for moving the lever to an inoperative position. 20

14. In a lock having a cam adapted to be rocked only by a master key for releasing a locking bolt, an alarm, means for operating the alarm, means for retaining the operating means against motion and including a rockable rod, a guide for the rod, a plunger connected to the rod and adapted to be rocked by the cam, means for adjustably positioning the rod in the guide so that the plunger may be properly positioned in the path of the rockable cam. 30

15. In a lock having a cam adapted to be rocked only by a master key for releasing a locking bolt, means at the room side of the lock for causing shifting of the bolt to locking position, a base plate, a housing removably secured to the plate, a clapper mounted on the plate, a bell secured to the inner wall of the housing and adapted when the housing is in place to enclose the clapper, means for operating the clapper, means actuated by the cam for setting the operating means in motion. 40

VIRGIL SIDNEY DOWNING.
